AUXILIARY ASH DIPPING APPARATUS, AND A METHOD OF DIPPING ASHES
AND CLINKERS, COMBINED, AND A DIPPER BOWL THEREFOR

UNITED STATES PATENT OFFICE

2,605,127

DIPPER

George M. Nicholson, Battle Creek, Mich.

Application March 31, 1948, Serial No. 18,260

5 Claims. (Cl. 294—9)

1

The present invention relates broadly to excavating apparatus, and in its specific phases to a side operated, split bowl, ash dipper.

With stoker fired house heating furnaces of the type now in common use, all of the ashes and clinkers have to be removed from the furnace fire pot through the doorway normally used for hand firing. These clinkers are commonly removed with a hook or hook-ended tongs, and the ashes with an ordinary shovel. Removing ashes in this manner from a furnace is far from satisfactory since the only ashes readily accessible to the shovel are those at the furnace doorway level, and some of those at the back of the furnace below doorway level. The shortcomings of this ash shoveling procedure and separate requirement of clinker tongs lead to the conception and development of the present invention.

Accordingly among the objects of the present invention is the provision of a new type of ash dipper adapted to remove ashes from a stoker fired house heating furnace above and below its doorway level from front to back of the fire pot of the furnace.

Another object is to provide an ash dipper which is also adapted to grip and pick up small clinkers in the furnace fire pot.

Another object is to provide a depending split bowl ash dipper with a side extending operating handle mechanism.

Another object is to provide the ash dipper with pivoted clam-shaped dipper jaws, which are preferably sharpened, and operable through an elongated operating handle assembly projecting sidewise therefrom coaxially with pivots of said jaws.

A still further object of the invention is to provide a device of this character which will possess advantages in points of efficiency and durability, is inexpensive to manufacture, and at the same time is simple in construction and operation.

Still further objects and advantages of the invention will appear as the description proceeds.

To the accomplishment of the foregoing and related ends, the invention, then, consists of the means hereinafter fully described and particularly pointed out in the claims, the annexed drawing and the following description setting forth in detail certain means for carrying out the invention, such disclosed means illustrating, however, but several of various ways in which the principle of the invention may be used.

In the annexed drawing:

Figure 1 shows a side view of a preferred form of the present invention,

2

Figure 2 shows a top view of the assembly illustrated in Figure 1.

Figure 3 shows an end view as taken at line 3—3 of Figure 1, looking in the direction of the arrows, with the bottom of the dipper bowl partially opened.

Figure 4 shows a fragmentary perspective view of a modified form of the bowl portion of the present invention.

10 Referring more particularly to Figures 1, 2, and 3 of the drawing, it will be noted that the dipper bowl 1 is formed in two parts indicated by the numerals 1a and 1b. Bowl member 1a is provided with extending ears 2, while bowl member 1b has inwardly depressed extending ears 3. All four of said ears are drilled in alignment for a purpose to be hereinafter described.

20 Welded to one of the ears 2 and in axial alignment with the openings in both of said ears 2, is an elongated tubular handle member 4 which preferably has sidewise projecting gripping members 5 suitably spaced from the free end of the handle member. Extending through this tubular handle member, for free rotation therein, is an inner handle member 6 which has a gripping member 7 at its free end, while the other end of said member 6 passes through ears 2 and 3 of bowl members 1a and 1b, and is preferably anchored, as by welding, to both of the ears 3 of bowl member 1b while acting as a pivot bearing for ear 2 at the outer end of bowl member 1a. To facilitate use of the assembly, the biting edges 14 of the bowl members 1a and 1b are preferably sharpened as shown in Figure 3.

25 In the place of the split hemispherical steel bowl shown in Figures 1, 2, and 3, the dipper assembly of the present invention may be made in any other suitable form, such as with a bowl, Figure 4, having substantially flat steel end panels 8, 9, 10, and 11, and curved steel side panels 12 and 13. This construction may be made either from stamped parts welded together with the ears in proper location, or it may be made as two complete stampings with ears in place, or with ears welded in place after stamping. On the other hand with the hemispherical bowl, the preferred procedure is to stamp a hemisphere of suitable size from heavy gage sheet metal, and split same to form members 1a and 1b, to which ears 2 and 3 may be welded in conventional manner after suitably offsetting the portion adjacent ears 3 to form the overlapping assembly construction shown in the drawing.

30 For home furnace ash dipping use a preferred size of the assembly involves the use of an 8" length bowl 1, and a $\frac{3}{4}$ " outside diameter tubular

steel handle member 4 approximately 42" long, with the center of the gripping members 5 being approximately 16" from the free end of handle member 4. The inner handle member 6 is preferably formed from $\frac{3}{8}$ " outside diameter steel rod and has a gripping member 7 which is approximately 5" long and formed from suitable size stock for hand gripping, for instance $\frac{3}{4}$ " round steel bar stock, brazed or welded in place.

To use the ash dipper of the present invention, the furnace door is opened and the bowl portion extended into the furnace fire pot (not shown). The bottom of the dipper bowl is pivotally opened by operating the handle members, and the bowl dropped down into the ashes with the bottom of the bowl down. By turning the handle members in the opposite direction the bottom of the bowl will be closed to take a bite from the bed of ashes. The dipper assembly is then removed, emptied, and returned to the furnace as before to continue the process until the surplus ashes in the fire pot of the furnace are removed. At the same time the bowl of the dipper assembly may be used to grip and remove small clinkers and thus avoid any necessity of requiring a tong type clinker remover.

Other modes of applying the principle of my invention may be employed instead of those explained, change being made as regards the article and combinations herein disclosed, provided the means stated by any of the following claims or the equivalent of such stated means be employed.

I therefore particularly point out and distinctly claim as my invention:

1. A hand tool of the character described, comprising an open top substantially closed bottom bowl, said bowl being non-telescoping and split, aligned ear means at the opposite sides of the upper edge of said bowl for use in hinged joining said split with said split extending from said ear means through the bottom of said bowl, a sidewise projecting handle member substantially in alignment with said aligned ears of said hinge means and rigidly joined to one side of one of said split sections of said bowl, a second handle member substantially coaxial with said first handle member and in alignment with said aligned ear hinge means, said second handle member being rigidly joined to the other of said split sections, and operating means on said handle members for use in rotating same relative to each other to open and close the bottom of said bowl.

2. In a hand operated ash dipper having an open top bowl, said bowl having a substantially closed bottom and being split crosswise through the bottom of said bowl into two substantially equal size mating bowl sections which are non-telescoping, aligned pivot means at the opposite sides of the upper portion of said bowl at the mating edges of same for use in pivotally hinging said bowl sections together, a tubular handle member rigidly fastened to one side of one of said bowl sections at said aligned pivot means and co-axial therewith, a second handle member within said tubular handle member and extending through said aligned pivot means on opposite sides of the open top of said bowl, said second handle member being rigidly anchored to the opposite edges of the second of said bowl sections and acting as the hinge upon which said first bowl sections can be rotatably supported by its ear at its edge opposite its ear fastened to said tubular handle, and means on said tubular handle member and said second handle member for use

in actuating said mating bowl sections to open and close the bottom of said bowl.

3. An ash dipper suitable for hand operation, which consists of an open top bowl, said bowl being split crosswise through the bottom of said bowl into two substantially equal size mating hollow bowl sections which are non-telescoping, overlapping ear means having aligned openings at the upper portion of the mating edges of said bowl sections for use in pivotally hinging said bowl sections together, an elongated tubular handle member rigidly fastened to one side of one of said bowl sections in axial alignment with said aligned pivot openings, a second handle member within said tubular handle member and extending coaxially therefrom across the top of said bowl and through said aligned openings in the overlapping aligned ear means on both sides of the open top of said bowl, said second handle member being rigidly anchored to the second of said bowl sections and acting in co-operation with the aligned ear remote from said tubular handle member as a trunnion upon which the first of said bowl sections can be supported and relatively move for rotatably opening and closing the bottom of said bowl, a sidewise projecting gripping member on said tubular handle member, and a gripping means on the free end of said second handle member, whereby relative rotation of the two handle members, and the actuation of said mating bowl sections for opening and closing of the bottom of said bowl, is facilitated.

4. An ash dipper suitable for hand operation, which consists of an open top bowl, said bowl being split crosswise through the bottom of said bowl into two substantially equal size mating hollow bowl sections which are non-telescoping, overlapping ear means having aligned openings at the upper portion of the mating edges of said bowl sections for use in pivotally hinging said bowl sections together, the ears of one of said bowl sections being adjacent but between the ears of the other of said bowl sections, the mating edges of said bowl sections being relatively sharp to facilitate dipping use, an elongated tubular handle member rigidly fastened to only one side of one of said bowl sections in axial alignment with said aligned pivot openings, a second handle member within said tubular handle member and extending coaxially therefrom across the top of said bowl and through said aligned openings in the overlapping ear means on both sides of the open top of said bowl, said second handle member being rigidly anchored to the ears of the second of said bowl sections at both edges thereof and acting as a projecting trunnion about which one of the ears which forms a trunnion bearing of the first of said bowl sections can relatively move during the opening and closing of the bottom of said bowl, a sidewise projecting gripping member on said tubular handle member, and a gripping means on the free end of said second handle member, whereby relative rotation of the two handle members, and the actuation of said mating bowl sections for opening and closing of the bottom of said bowl, is facilitated.

5. In a dipper having a substantially vertically split non-telescoping bowl open at its top and adapted to be closed and opened at its bottom for filling and emptying purposes, and wherein said split bowl is mounted on an elongated handle having inner and outer concentric members which extend outward from the side of said

bowl substantially at the top of the split thereof, said concentric members having operating members for use in rotating one concentric member relative to the other for hingedly opening and closing said split bowl at its bottom, the combination therewith of ears on opposite sides of said split bowl members with all of said ears perforated in alignment on the axis about which said split bowl members pivot for filling and emptying purposes, the outer concentric member of said elongated handle being rigidly fastened to the outer ear of one of said split bowl members in alignment with said pivot axis, and the inner of said concentric members of said elongated handle passing through all of said ears on said pivotal axis and rigidly anchored to both of the ears of the other of said split bowl members while forming a trunnion bearing for the ear at the opposite side of said split bowl

member from said ear thereof on which said outer handle member is rigidly fastened.

GEORGE M. NICHOLSON.
